UNITED STATES PATENT OFFICE.

CHARLIE W. PETERSON, OF GRAYSON, NEBRASKA.

PERMUTATION-PADLOCK.

1,241,435.

Specification of Letters Patent. Patented Sept. 25, 1917.

Application filed March 27, 1917. Serial No. 157,796.

To all whom it may concern:

Be it known that I, CHARLIE W. PETERSON, a citizen of the United States, residing at Grayson, in the county of Sheridan and 5 State of Nebraska, have invented certain new and useful Improvements in Permutation-Padlocks, of which the following is a specification.

This invention relates to a permutation padlock and the primary object of the invention is to provide a locking mechanism arranged within a casing and adapted to be so operated by a person understanding the combination of the lock as to permit the 15 shackle to be unlocked without the use of keys or the like.

The invention also has for one of its objects to provide a pair of coöperating barrels having helical raised portions adapted 20 to coöperate with the locking mechanism for unlocking the shackle of the lock when the barrels are properly rotated at predetermined intervals.

Another object of the invention is to provide a device of this character that may be operated by a pair of keys extending exteriorly of the casing, either one of which may be easily turned at any time but which will require proper pre-determined movement imparted alternately to the keys to 30 accomplish the desired result.

A further object of this invention is the provision of a permutation padlock which consists of comparatively few parts and is 35 simple in construction, but durable and well adapted to withstand the rough usage to which devices of this character are ordinarily subjected.

For a full description of the invention 40 and the advantages and merits thereof, reference is to be had to the following description and the accompanying drawings, wherein is illustrated the preferred form of my invention, in which;

45 Figure 1 is a longitudinal section through the lock casing, disclosing the operating mechanism mounted therein.

Fig. 2 is a section on the line 2—2 of Fig. 1.

50 Fig. 3 is an end view, disclosing the different positions taken by the key handles

during the operation of the locking mechanism for unlocking the shackle.

Referring to the drawing, wherein is illustrated the preferred form of my invention, 55 and in which like numerals of reference indicate corresponding parts throughout the several views, the casing 1 may be of any preferred shape and has pivoted in one end, the shackle 2 the opposite end of which projects through an opening in the end of the casing to be locked in position within the casing when the shackle is closed. Mounted within the casing at the opposite end thereof is a bracket 3 which comprises a strip of 60 material having its intermediate portion secured to the end wall of the casing by a suitable fastening element 4. From this point, the ends of the bracket are bent to be disposed in spaced relation to the end wall of 65 the casing. Mounted upon the ends of the brackets is a pair of barrels 5 and 6. The central portion of each barrel has a square opening for the reception of the shanks 7 of the operating keys 8. The operating keys 75 project outwardly beyond the end of the casing so that they may be operated from the exterior thereof. The opposite ends of the barrels are each provided with short journals, mounted in openings provided in a 80 shelf 9 extending transversely across the casing between the side walls thereof and engaged with the end of each barrel, so that the said barrels are rotatably mounted and operate between the shelf 9 and the ends of 85 the bracket 3.

The free end of the shackle within the casing is provided with a notch 10 adapted to be engaged by the end of a locking latch 11, pivotally mounted within the casing. 90 The locking latch has an arm 12 through which is extended an operating rod 13 having a head 14 formed on its terminal. The opposite end of the operating rod is extended through a central opening in the 95 shelf 9, and has its terminal provided with a connecting rod 15 which comprises a short length of rod exactly equal in length to the distance between the proximate surfaces of the barrels 5 and 6. This rod is, therefore, 100 disposed at right angles to the operating rod 13 and is preferably integrally formed

therewith. The ends of the rod 15 are normally in engagement with the surfaces of the barrels 5 and 6. A collar 16 is mounted intermediate the ends of the rod 13, and a 5 coil expansion spring 17 is interposed between the collar and the shelf 9, thereby tending to hold the head 14 in raised position, and the connecting rod 15 also in raised position.

10 The barrel 5 is provided adjacent each end with a helical rib or raised thread 18. The upper and lower ribs are independent of each other as clearly shown by Fig. 1, and the lower terminal of the upper rib is spaced 15 above the upper terminal of the lower rib for a distance substantially equal to the pitch of the said helical ribs. On the barrel 6, I have provided a rib 19 disposed intermediate the ends of the barrel 6, and of helical formation and having its terminals spaced apart for a distance equal to the space between the adjacent ends of the helical ribs on the barrel 5.

20 Assuming the parts to be in the position 25 shown by Fig. 1 of the drawing, the operation of the device will be as follows:

The key 8 fixed to the barrel 5, will be 30 rotated to complete three-quarters of a complete turn. During this movement, the helical rib 18 at the upper end of the barrel 5 will engage the end of the rod 15, and force the same downwardly against the action of the coil spring 17. This will bring the opposite end of the connecting rod 15 35 below the end of the helical rib 19 on the barrel 6. This barrel will then be rotated for three-quarters of a turn by its corresponding key. This will bring the two keys 8 to the positions shown by dotted lines in 40 Fig. 3, and designated as the first and second positions. This rotation of the barrel 6 will bring the connecting rod 15 downwardly so that the opposite end will be disposed beneath the end of the lower helical rib 18 45 on the barrel 5. The key 8, of the barrel 5, will again be rotated, but this rotation need only continue until such time as the head 14 engages on the arm 12 to tilt the latch for disengaging the same from the 50 notch 10. The shackle 2 may then be opened. For placing the latch back into operative position, it is merely necessary to turn the keys to permit the spring 16 to raise the connecting rod 15, since it will be 55 observed that the ends of each helical rib are spaced apart sufficiently to permit the longitudinal passage of the rod 15. The flat spring 20 engaged with the latch tends to normally hold the same in locked position.

60 From the foregoing it will be observed that a very simple and durable permutation padlock has been provided, the details of which embody the preferred form. I desire

it to be understood, however, that slight changes in the minor details of construction 65 may be made without departing from the spirit of the invention or the scope of the claims hereunto appended.

I claim:

1. A lock comprising a casing having barrels mounted therein, the barrels being arranged in spaced relation and provided with helical threads extending partially around the cylinder, operating means disposed within the casing and associated with the said 75 cylinders whereby engagement with the said helical threads will operate the said operating means when the barrels are rotated, a shackle, and a latch associated with the operating means and engageable with the 80 said shackle.

2. A lock comprising a casing provided on its interior with a pair of spaced apart barrels, means exteriorly mounted for rotating the barrels, an operating rod having a 85 connecting rod, the terminals of which engage the proximate surfaces of the barrel, and means mounted on the barrels and engageable with the ends of the said connecting rod for longitudinally moving the said 90 rod when the barrels are rotated by the said means.

3. A lock comprising a casing having a latch pivotally mounted therein, a shackle engageable with the latch for holding the 95 shackle in locked position, an operating rod, a pair of barrels rotatably mounted and arranged in spaced relation, a connecting rod carried by the operating rod and engageable with the proximate surfaces of the barrels, 100 one of said barrels having a pair of helical threads, the other barrel having a single helical thread, and means for rotating the barrels whereby engagement of the said threads with the said connecting rod will 105 move the latter longitudinally for releasing the said latch.

4. A lock comprising a casing having a shackle mounted thereon and provided with a latch pivotally mounted to engage the 110 shackle, a bracket mounted in the casing, a pair of barrels rotatably mounted on the bracket and provided with helical threads extending partially around each barrel to provide spaces between the terminals of the 115 threads, an operating rod engageable with the latch, and a connecting rod carried by the operating rod and co-operating with the said threads to move the operating rod when the said barrels are rotated.

5. A lock comprising a casing having a shackle mounted thereon and provided with a latch pivotally mounted to engage the shackle, a bracket mounted in the casing, a pair of barrels rotatably mounted on the 125 bracket and provided with helical threads

extending partially around each barrel to provide spaces between the terminals of the threads, an operating rod engageable with the latch, a connecting rod carried by the 5 operating rod and coöperating with the said threads to move the operating rod when the said barrels are rotated, and an expansible element mounted on the operating rod for moving the latter back to normal position

after the said connecting rod has been re- 10 leased from engagement with the threads.

In testimony whereof I affix my signature in presence of two witnesses.

CHARLIE W. PETERSON.
